(57) **CLAIM**

The ornamental design for a battery, as shown and described.

DESCRIPTION

FIG. 1 is a front, top and right side perspective view of a first embodiment of a battery showing our new design;

FIG. 2 is a rear, top and left side perspective view thereof;

FIG. 3 is a front view thereof;

FIG. 4 is a rear view thereof;

FIG. 5 is a top plan view thereof;

FIG. 6 is a right side view thereof;

FIG. 7 is a left side view thereof;

FIG. 8 is an enlarged cross-sectional view of an upper portion of the article taken along line 8-8 in FIG. 3 with the internal structure omitted;

FIG. 9 is an enlarged cross-sectional view of an upper portion of the article taken along line 9-9 in FIG. 5 with the internal structure omitted;

FIG. 10 is a front, top and right side perspective view of a second embodiment of a battery showing our new design;

FIG. 11 is a rear, top and left side perspective view thereof;

FIG. 12 is a front view thereof;

FIG. 13 is a rear view thereof;

FIG. 14 is a top plan view thereof;

FIG. 15 is a right side view thereof;

FIG. 16 is a left side view thereof;

FIG. 17 is an enlarged cross-sectional view of an upper portion of the article taken along line 17-17 in FIG. 12 with the internal structure omitted;

FIG. 18 is an enlarged cross-sectional view of an upper portion of the article taken along line 18-18 in FIG. 14 with the internal structure omitted;

FIG. 19 is a front, top and right side perspective view of a third embodiment of a battery showing our new design;

FIG. 20 is a rear, top and left side perspective view thereof;

FIG. 21 is a front view thereof;

FIG. 22 is a rear view thereof;

FIG. 23 is a top plan view thereof;

(Continued)

FIG. 24 is a right side view thereof;
 FIG. 25 is a left side view thereof;
 FIG. 26 is an enlarged cross-sectional view of an upper portion of the article taken along line 26-26 in FIG. 21 with the internal structure omitted; and,
 FIG. 27 is an enlarged cross-sectional view of an upper portion of the article taken along line 27-27 in FIG. 23 with the internal structure omitted.
 The features shown in broken lines in the drawings depict environmental subject matter only and form no part of the claimed design. The dashed-dotted lines denote the boundary of the claim and form no part of the claimed design.
